Primary Examiner — Garth Rademaker*Assistant Examiner* — Richard Kearney(74) *Attorney, Agent, or Firm* — Davis & Bujold PLLC;
Michael J. Bujold(57) **CLAIM**

I claim the ornamental design for a customizable ring, as shown and described.

DESCRIPTION

FIG. 1 is an exploded view of a customizable ring according to the present invention;

FIG. 2 is a left side elevation view of the customizable ring, the right side elevation view being a mirror image thereof; FIG. 3 is a cross section view taken along line 3-3 of FIG. 2; and,

FIG. 4 is a front elevation view of the customizable ring, the rear elevation view being a mirror image thereof.
